UNITED STATES PATENT OFFICE.

CHARLES TRUNICK, OF FARRELL, PENNSYLVANIA.

SCREW DRIVER.

1,418,184.

Specification of Letters Patent. Patented May 30, 1922.

Application filed August 12, 1920, Serial No. 402,938. Renewed April 7, 1922. Serial No. 550,515.

To all whom it may concern:

Be it known that I, CHARLES TRUNICK, a citizen of the United States, residing at Farrell, in the county of Mercer and State of Pennsylvania, have invented certain new and useful Improvements in Screw Drivers; and I do declare the following to be a full, clear, and exact description of the invention, such as will enable others skilled in the art to 10 which it appertains to make and use the same.

This invention relates to an improved screw-driver and one object of the invention is to provide a screw-driver having an im- 15 proved handle construction including as one of its parts an improved socket for releasably holding a removable bit.

Another object of the invention is to so construct the socket that the bit may be 20 easily thrust into place and the securing sleeve then moved of its own accord to the locking position.

Another object of the invention is to so construct the socket that the same may in- 25 clude a spring serving to discharge the bit from the socket when the securing sleeve is moved to the releasing position.

Another object of the invention is to so construct the securing sleeve that it may be 30 limited in its rotary movement and yieldably held against rotary movement and thus caused to normally remain in the locking position and to return to the locking position when released after being moved to the re- 35 leasing position.

Another object of the invention is to pro- 40 vide a screw driver of the removable bit type in which the bit may be easily and quickly put in place and removed and which will be securely held in place when placed in the socket and prevented from having any move- 45 ment, thus providing a substantially solid construction when the bit is in place.

Another object of the invention is to so 50 construct the screw-driver that it will be very strong and durable and not be liable to break when in use.

This invention is illustrated in the accompanying drawings, wherein:

Figure 1 is a view showing the improved screw-driver in side elevation, a ring carried by the locking sleeve being shown in section. 55

Figure 2 is a view similar to Fig. 1 show-

ing the bit thrust entirely into the socket 55 and the locking sleeve turned from the position in Fig. 1 to the locking position.

Figure 3 is a sectional view taken along the line 3—3 of Fig. 1.

Figure 4 is a transverse sectional view 60 taken along the line 4—4 of Fig. 2.

Figure 5 is a transverse sectional view taken along the line 5—5 of Fig. 3.

Figure 6 is a perspective view showing the bit partially inserted, as shown in Fig. 1. 65

Figure 7 is a perspective view showing the bit entirely inserted and the locking sleeve in the locking position as shown in Fig. 2.

Figure 8 is a perspective view of the for- 70 ward end portion of the handle showing the locking sleeve removed.

This improved screw-driver is provided with a handle including a metal sleeve 1 in which is received the stock 2 formed of wood and held in place by the usual pin 3. The 75 handle is provided with an outstanding collar 4 and the collar carries a pin 5 the purpose of which will hereinafter be brought out. The forward end portion of the handle is provided with oppositely disposed slots 6 which communicate with the longitudinally extending opening or pocket 7 so that the bit 8 which fits into this pocket will be held against rotary movement by the side pins 9 fitting into the slots 6. 80 The end portions of the pins 9 will extend beyond the neck portion 10 of the handle for fitting into bayonet slots 11 formed in the sleeve 12 which sleeve is rotatably mounted upon the neck 10 and limited in its rotary 85 movement by a pin 13 which is carried by the neck and extends through a slot 14 formed in the sleeve. This sleeve 12 carries a collar 15 which fits upon the collar 4 and carries a pin 16 similar to the pin 5. The 90 pins 5 and 16 are passed through the eyes at the end of the spring 17 and it will thus be seen that when the sleeve is rotated to bring the bayonet slots 11 into registry with the slots 6, the spring will be stretched and 95 will serve to return the sleeve to its normal locking position as soon as the sleeve is released. It will thus be seen that with the sleeve turned to the position shown in Fig. 100

1, the bit can be inserted and moved in- 105 wardly with the end portions of the pins 9 passing through the slots 6 and 11. As soon as the end portions of the pins have passed

into the inner end portions of the bayonet slots, the spring 17 will contract and rotate the sleeve to the locking position of Fig. 2. This will serve to hold the screw-driver bit 5 tightly in place until it is desired to remove the bit and insert a new one. When it is desired to remove the bit, it is desired to have the bit easy of removal and when the screw driver is in use, it is desired to have 10 the bit pressed outwardly to hold the pins in engagement with the walls of the bayonet slots.

There has, therefore, been provided a spring 18 which is positioned in the pocket 7 15 and has its inner end passed through an opening formed in the pin extension 19 of the block 20, positioned in the inner end of the pocket and secured by a pin 21. The outer end portion of this spring 18 passes 20 through an opening formed in the pin extension 22 of the block 23 and this block 23 has its outer ends cupped for receiving the end of the bit. Therefore when the bit is 25 pressed inwardly, it will engage the block 23 and move the same inwardly against the action of the spring 18 thus compressing the spring. Therefore when the sleeve is rotated and moved from the locking position to the releasing position of Fig. 1, the spring 30 18 will expand and drive the bit out of the socket.

It is therefore evident that the bit can be put in place with the sleeve turned to the releasing position and then pressed inwardly 35 until the securing or locking sleeve is released and moved to the locking position. The bit will be securely held in place and there will be no danger of the securing sleeve accidentally moving to a releasing 40 position. When, however, it is desired to remove the bit, it is simply necessary to rotate the sleeve to the releasing position and

the spring 18 will act to expel the bit thus making it easy to remove the bit and put a new one in place. A covering ring or bushing 45 24 is placed upon the sleeve and covers the slots 11 and 14 thus hiding these slots and further preventing the slots from becoming choked or the hand of the operator being cut while using the device. 50

What is claimed is:

A screw driver comprising a handle having a longitudinally extending socket formed therein, a collar formed upon the handle intermediate the depth of the socket, 55 the forward end portion of the handle having longitudinally extending side slots cut from its end and communicating with the socket, a sleeve rotatably mounted upon the forward end portion of the handle and having bayonet slots cut from its end for registering with the slots of the handle, the sleeve having an outstanding collar fitting upon the collar of the handle and forming a spring housing, a pin extending from the 60 handle through an angular slot formed in the sleeve to limit rotary movement of the sleeve, pins carried by the sleeve and collar of the handle and extending longitudinally of the handle in opposite directions within the spring housing, a spring positioned 65 within the spring housing and having connection with the pins of the sleeve and handle collar to yieldably retain the sleeve against rotary movement out of a locking position, a 70 protector sleeve fitting upon the slotted sleeve and outer end portion of the side pin, and a bit fitting into the socket and having side pins for fitting into the registering slots of the 75 sleeve and handle.

In testimony whereof I have hereunto set my hand.

CHARLES TRUNICK.
